UNITED STATES PATENT OFFICE.

WILLIAM P. GRAHAM, OF BROOKLYN, NEW YORK.

DESIGN FOR A COVERED DISH.

45,002.

Specification for Design.

Patented Dec. 9, 1913.

Application filed February 1, 1913. Serial No. 745,746. Term of patent 7 years.

To all whom it may concern:

Be it known that I, WILLIAM P. GRAHAM, a citizen of the United States, residing at Brooklyn, in the county of Kings and State of New York, have invented a new, original, and ornamental Design for Covered Dishes, of which the following is a specification, reference being had to the accompanying drawing, forming a part thereof.

Figure 1 is a side elevation of a covered

dish showing my design, Fig. 2 is an end elevation thereof and Fig. 3 is a plan view thereof.

I claim—

The ornamental design for a covered dish as shown.

WILLIAM P. GRAHAM.

Witnesses:

DOROTHY BRODMANN,

HUGO MOCK.
